US00D900227S

(12) **United States Design Patent** (10) **Patent No.:** **US D900,227 S**
Jung (45) **Date of Patent:** **** Oct. 27, 2020**

(54) **CASE FOR HANDHELD ELECTRONIC GAME**

(71) Applicant: **SPIGEN KOREA CO., LTD.**, Seoul (KR)

(72) Inventor: **Soo Ha Jung**, Seoul (KR)

(73) Assignee: **SPIGEN KOREA CO., LTD.**, Seoul (KR)

(**) Term: **15 Years**

(21) Appl. No.: **29/718,625**

(22) Filed: **Dec. 26, 2019**

(51) LOC (12) Cl. **21-01**

(52) U.S. Cl.

USPC **D21/333**

(58) **Field of Classification Search**

USPC D14/203.3-203.7, 439, 251-253, 447, D14/217, 240, 248, 238.1, 440, 250, 454; D13/103, 107-108, 119; D3/201, 218, D3/247, 249, 269, 273, 301, 303; D21/333

(57) **CLAIM**

The ornamental design for a case for handheld electronic game, as shown and described.

DESCRIPTION

FIG. 1 is a front perspective view of a case for handheld electronic game showing my new design;

FIG. 2 is another front perspective view thereof;

FIG. 3 is a rear perspective view thereof;

FIG. 4 is another rear perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

1 Claim, 10 Drawing Sheets
